United States Patent Office

Des. 186,784
Patented Dec. 1, 1959

186,784

PENDANT

Dora A. Pope, Merino, Colo.

Application June 12, 1959, Serial No. 56,320

Term of patent 14 years

(Cl. D45—16)

The essential features of the present design are shown in solid lines.

I claim:

The ornamental design for a pendant, as shown and described.
